DRAFT CONTROL DAMPER

Robert Wilson, Holland, Mich., assignor to Holland Furnace Company, Holland, Mich., a corporation of Delaware

Application May 7, 1945, Serial No. 592,509

10 Claims. (Cl. 236—45)

1

This invention relates to a draft control damper and more particularly to a damper that is controlled primarily by the amount of suction in the flue; and may also be opened manually or mechanically by means permitting further opening of the damper by the flue suction if the latter predominates thereover.

Among the objects of my invention are: to provide a novel and improved draft control damper; to provide a draft control damper in which there is embodied a novel means for positively and selectively assisting the opening of the damper manually or mechanically without interfering with further opening by the suction in the flue should the latter predominate; to provide a novel arrangement of operating parts for a draft control damper; to provide a novel arrangement of damper and weights therefor; and to provide a novel mounting means for a damper.

Other objects, advantages and capabilities, inherently possessed by my invention, will appear more fully from the following detailed description taken in connection with the accompanying drawings.

In the drawings:

Fig. 1 is a front elevation of a draft control damper means embodying my invention.

Fig. 2 is an edge elevation of the frame and the damper with its associated parts, the pipe leading to the smoke pipe being shown in central vertical section.

Fig. 3 is a vertical section through the line 3—3 of Fig. 1 but showing the damper as being partially open.

Fig. 4 is a plan view with a portion of the frame broken away and looking from the line 4—4 of Fig. 1 in the direction of the arrows.

Fig. 5 is an enlarged fragmentary section along the line 5—5 of Fig. 1.

While my invention resides in the combination, construction and arrangement of parts illustrated in the drawing, I have shown therein, for illustrative purposes, a preferred embodiment, and wish it understood that the same is susceptible of modification and change without departing from the spirit and scope of the appended claims.

Referring more in detail to the drawing, my novel and improved draft control damper is mounted upon the outer end of a stub pipe 1, leading into the side of a furnace smoke pipe 2 which connects in the usual manner to the flue for carrying away the smoke and products of combustion from the furnace. This type of control damper lessens the fuel consumption and enables a more efficient and complete combustion.

in the fire box of the furnace by reason of the bottom portion of the damper swinging inwardly when the suction in the flue and smoke pipe is such as to cause such inward movement. A frame 3 is fixedly mounted in the outer end of the pipe 1 and as seen in Fig. 1 is in the form of a ring having an outer annular flange 4 preferably abutting against the outer edge of the pipe. Ring 3 is formed at its inner edge with narrow, radially extending, annular flanges 5 and 6, the latter of which is positioned a slight distance forwardly of flange 5. Flange 5 terminates a distance above the center line of pipe 1, while flange 6 extends a distance above this center line on the left hand side of Fig. 1, and short of this center line on the right hand side of Fig. 1.

As seen in Figs. 1 and 2, ring 3 is annular at its forward edge but at each of its two side edges is formed with a flattened inset portion 7 upon the rear edges of which the flange 6 terminates at the different heights referred to above. Fixed by screws or the like 8 to the flattened sides 7 of the ring, upon each side thereof, is a fulcrum bracket 10 having a rearwardly extending ear 11, which ear is bent into a U-shape to form the outer imperforate wall 12. Each of the walls 12 is formed with an elongated slot 14 having a curved bottom edge, in which elongated slots are rollably and rockably mounted the ends of the fulcrum rod 15. This rod is of such length that its outer ends will be prevented from having any substantial longitudinal movement by the outer imperforate walls 12 of the bracket ears 11. Fixed to the fulcrum rod 15 is a damper 17 swingably mounted with relation to the frame. To effect this mounting of the damper upon the fulcrum rod the screws 16, at laterally spaced positions on the damper, pass through the downwardly extending legs of straps 18, the upper portions of each of which straps pass around the fulcrum rod and are clamped fixedly thereto by said screws so that the damper will be fixed to rotate with the fulcrum rod.

Fixed to the damper 17 at a point a slight distance below the fulcrum rod and laterally in the center thereof, is an elongated screw 19 upon which is threaded a two-part weight member 20 which, upon rotation in one direction or the other, will be moved toward or away from the damper 17 to adjust the tendency of the weight to effect by gravity a greater or less closing movement of the damper. Adjacent the fulcrum rod 15 the damper is offset forwardly at 21 so that the upper offset portion will be seated on or near the front side of flange 5 and the lower portion of the damper will be seated against or near the

rear face of flange 6, when the damper is in vertical position. Fixed to the rear face of the upper offset portion of the damper is a weight element 22, which at its outer edges is inset a slight distance from the top edge of the damper so as to permit said inset portion 23 to seat against or near flange 5 when the damper is vertical.

Positioned outside of the frame or ring 3 is an arm 24 extending rearwardly and preferably at an angle downwardly, the upper end 25 of this arm extending to the inside of the forward edge of ring 3 and then extending rearwardly at 26 adjacent the inner face of the flattened portion 7. At its rear end this rearwardly extending portion 26 of the arm is provided with an aperture 27 through which rotatably extends the fulcrum rod 15. A slight distance back of the aperture 27, the rearwardly extending end 9 of portion 26 of arm 24 is bent at right angles (Fig. 4) in the form of an extended arm 28, arcuate in shape, and at its far end bent to form a flange 29 which is provided with an aperture 30 rotatably receiving the fulcrum rod 15.

As seen in Fig. 3 the arcuate extension 28 of arm 24, when arm 24 is moved upwardly at its free end, presses against the inner face of the fixed weight 22 to move the upper side of the damper outwardly and the lower side inwardly. As will be understood in Fig. 3, this manual or mechanical movement of arm 24, to cause its inner extension 28 to press against the rear face of the top of the damper, will positively open the damper a desired amount, but will not prevent the damper from being open a further amount by suction in the flue if such suction is great enough to open the damper a greater amount than that afforded by the arm 24. The outer free end portion of arm 24 is provided with any suitable number of apertures 31 through which may be connected the lower end of a chain, cord or other element (not shown) for moving arm 24 either manually or mechanically as desired.

From the above it is seen that I have provided a novel arrangement of weights, one of which may be adjusted as desired to effect desired balance of the damper with relation to the suction in the flue, and also a novel arrangement of parts by which the damper may be manually or mechanically opened a desired amount and the damper be free to open a greater amount should the suction in the flue be sufficient to cause the damper to open to such greater amount. In other words, the manual or mechanical means for opening the damper, effects such opening to a desired amount but leaving the damper free to be opened a greater amount should conditions in the flue necessitate.

It is to be noted in Fig. 5 that the fulcrum rod 15 is rollably and rockably mounted at its two ends on the arcuate bottom edges of the two slots 14 in the ears 11. This causes the ends of the fulcrum rod to roll toward the forward end of slot 14 as the damper opens and to normally be seated in the middle of the arcuate bottom edge of these slots when the damper is vertical.

I claim:

1. A draft control damper comprising a frame, a fulcrum bracket on each side of the frame, each of said brackets having a U-shaped ear forming an outer imperforate wall and an inwardly spaced inner wall having an elongated slot with an arcuate concave bottom edge, a damper, a fulcrum rod fixed to said damper extending transversely thereof above its middle

and having ends extending beyond the side edges of the damper, said extended ends passing through said slots and held against excess longitudinal movement by the imperforate outer walls 5 and rollably mounted on said arcuate bottom edges of the slots, a control arm swingably mounted on the fulcrum rod and having an extended end outside of the frame, and a laterally spaced arm positioned inside of the frame, 10 said latter arm being bent at an angle to extend arcuately across the inside of the frame and having at its extended end a flange rotatably mounted on the fulcrum arm whereby, when the outer end of the control arm is moved in one direction, the arcuate extended inner end will bear against the inner face of the damper but permit the damper to be further opened by an excess amount of suction in the flue, a weight fixed to the damper above its axis of rotation, and a weight carried by the damper and adjustably mounted for movement toward and away from the damper.

2. A draft control damper comprising a frame, a fulcrum bracket on each side of the frame, each of said brackets having a U-shaped ear with an apertured inner wall and an imperforate outer wall, a damper, a fulcrum rod on said damper, said rod having extended ends each passing through one of the apertured inner walls 25 of the ears and prevented from excess longitudinal movement by the imperforate outer walls, an angle arm having its free end outside of the frame and its opposite end inside of the frame 30 behind the damper, said opposite end being fulcrumed on the fulcrum rod and having a portion extending above the fulcrum rod, the aperture in each of said inner walls being in the form of an elliptical slot to provide a limited amount of rolling movement of the fulcrum rod ends in the slots.

3. A draft control damper comprising a frame adapted to be mounted in an opening leading to a furnace flue, a damper having fixed thereon above its middle a fulcrum rod extending beyond the side edges of the damper, means for mounting the extending ends of the rod to the frame so that the damper may have swinging movement with relation to the frame, and an arm pivotally mounted on said rod and having an extension loosely contacting one face of the damper, said damper having a fixed weight above and an adjustable weight below the fulcrum rod, said arm having its free end outside of the frame whereby movement of the arm in one direction 45 will open the damper but permit further opening of the damper by suction in the flue.

4. A draft control damper comprising a frame adapted to be mounted in an opening leading to a furnace flue, a damper having fixed thereon above its middle a fulcrum rod extending beyond the side edges of the damper, means for mounting the extending ends of the rod to the frame so that the damper may have swinging movement with relation to the frame, and an arm pivotally mounted on said rod and having an extension loosely contacting one face of the damper, said arm having its free end outside of the frame whereby movement of the arm in one direction 50 will open the damper but permit further opening of the damper by suction in the flue.

5. A draft control damper comprising a frame, a fulcrum bracket on each side of the frame, each of said brackets having a U-shaped ear with an apertured inner wall and an imperforate outer 55 wall, a damper, a fulcrum rod on said damper,

said rod having extended ends each passing through one of the apertured inner walls of the ears and prevented from excess longitudinal movement by the imperforate outer walls, an angle arm having its free end outside of the frame and its opposite end inside of the frame behind the damper, said opposite end being fulcrumed on the fulcrum rod and having a portion extending above the fulcrum rod.

6. A draft control damper comprising a frame adapted to be mounted in an opening leading to a furnace smoke pipe, a damper swingably mounted in the frame on trunnions above the middle of the damper, and an arm member having an extension adapted to loosely contact one face of the damper, said damper and arm having a common axis of rotation on said trunnions, said trunnions having a limited amount of rolling movement forwardly and rearwardly of the frame, said arm having its free end outside of the frame whereby movement of the arm in one direction will open the damper but permit further opening of the damper by suction in the flue.

7. A draft control damper comprising a frame, a damper having a fulcrum rod for swingably mounting the damper in the frame, an angle arm pivotally mounted on said rod and including an extension, a portion of the arm being outside of the frame and the extension being inside the frame so that when the free end of the arm outside of the frame is moved in one direction the extension inside of the frame will push the top part of the damper outwardly to swing the bottom part inwardly a desired amount and also leave the damper free for further inward movement at its bottom portion.

8. A draft control damper comprising a frame adapted to be mounted in an opening leading to a furnace smoke pipe, a damper swingably mounted in the frame, an angle arm rotatably mounted with relation to said frame and said damper and having an extension loosely contacting the inner face of the damper above its axis of rotation whereby upward movement of the free

5 end of the arm will cause the extension to move the upper part of the damper free for further opening by suction in the smoke pipe, the arm and the damper having a common axis of rotation.

9. A draft control damper comprising a frame adapted to be mounted in an opening leading to a furnace smoke pipe, a damper swingably mounted in the frame, an angle arm rotatably mounted with relation to said frame and said damper and having an extension loosely contacting the inner face of the damper above its axis of rotation whereby upward movement of the free end of the arm will cause the extension to move the upper part of the damper free for further opening by suction in the smoke pipe, the fulcrum of said damper having a limited amount of rolling action forwardly and rearwardly of the frame as the damper is operated.

10. A draft control damper comprising a frame adapted to be mounted in an opening leading to a furnace smoke pipe, a damper swingably mounted in the frame, an angle arm rotatably mounted with relation to said frame and said damper and having an extension loosely contacting the inner face of the damper above its axis of rotation whereby upward movement of the free end of the arm will cause the extension to move the upper part of the damper free from further opening by suction in the smoke pipe.
